UNITED STATES PATENT OFFICE.

ROBERT McC. JOHNSTONE, OF ROSELLE PARK, NEW JERSEY, ASSIGNOR TO CAMERON MACHINE COMPANY, OF BROOKLYN, NEW YORK, A CORPORATION OF NEW YORK.

CORE-SUPPORTING MEANS.

Original application filed May 2, 1923, Serial No. 636,133. Divided in part and this application filed April 16, 1925. Serial No. 23,706.

This invention relates to core-supporting means and has for its main object and feature an expandible mandrel that will engage a core member and hold in undisturbed relation a group of individual cores produced from said core member.

This application is a division in part of one filed May 2, 1923, Ser. No. 636,133.

In the accompanying drawings the invention is disclosed in several concrete and preferred forms in which:

Fig. 1 is a view, partly in elevation and partly in section, of one end of a winding shaft with cores and coils of flexible material in position.

Fig. 2 is a view, partly in elevation and partly in section, of a winding shaft with a tube or core member in position before it is divided into sections or individual cores.

Fig. 3 is a perspective view of the winding shaft and core-cutting elements.

Figs. 4 to 8 inclusive show a modified form of the invention.

Fig. 4 is a view, partly in elevation and partly in section, of a winding shaft with cores and coils of flexible material in position and showing the clamping or gripping member in active position.

Fig. 5 is a transverse sectional view on the line 5—5 of Fig. 4, showing the clamping or gripping member in active position.

Fig. 6 is a view similar to Fig. 5, with the clamping or gripping member in inactive position.

Fig. 7 is a view somewhat similar to Fig. 4 but showing the core uncut and devoid of coils of flexible material and the clamping member in inactive position.

Fig. 8 is a transverse sectional view on the line 8—8 of Fig. 7.

Reference character 1 denotes a winding shaft having a longitudinal groove 2 in which clamping member 3 is seated. Said clamping member is slidable longitudinally in the groove of the shaft and is also capable of outward movement. Any suitable means may be employed for this purpose, but preferably member 3 is provided with elongated, oblique cam slots 4 through which project pins 5 fixed in the shaft. It will be understood that by moving member 3 lengthwise the cam action between the pins and slots is such that member 3 moves outwardly beyond the outer surface of the shaft so that, if a

tube as 6 has been placed upon the shaft, 55 serrated edges 7 of member 3 will become embedded in the soft interior surface of said tube and will hold said tube firmly in position. A convenient means for effecting the lengthwise movement of member 3 is here 60 shown in the form of threaded member 8 fitting on reduced and threaded portion 9 of the winding shaft. By rotating said member 8 in one direction, the clamping member may be moved lengthwise in one direction and, by 65 rotating member 8 in the other direction, gravity will restore the clamping member to its original position. Shaft 1 is further provided with circumferential grooves 10 that register with core-cutting elements 11 of the 70 core-cutting machine, and member 3 is provided with cut-away portions 12 that come into alinement with grooves 10 when said member 3 occupies its protruding position so that clearance for cutting elements 11 may 75 be obtained.

Normally, member 3 will occupy a position below the outer surface of the shaft. A relatively long cardboard tube 6 is then mounted on the shaft and member 3 is caused 80 to clamp said tube by being moved into its expanded position. The shaft is now inserted in a tube-cutting machine. Cutters 11 are spaced to match the slitting elements of a slitting and winding machine and it will be 85 understood that when shaft 1 and tube 6 are pressed against cutters 11 and the latter are rotated a group of cores will be produced that will be retained in undisturbed position 90 on the shaft. The shaft may then be removed from the cutting machine and inserted into a slitting and winding machine and coils of flexible material wound on the cores in proper alinement. After the winding operation is completed, the shaft is re- 95 moved from the machine and member 3 is withdrawn from engagement with the cores and the cores and coils are then readily removable from the shaft.

In Figs. 4 to 8 inclusive a modified form 100 of the invention is shown.

13 is a winding shaft suitably constructed to receive a rock member 14 extending longitudinally through the shaft and disposed eccentrically therein, and this rock member has a plurality of pins 15 arranged in a line 105 and adapted to clamp or grip the soft core under certain conditions. Suitable confin-

ing means, such as guide 16, are employed to hold the rock member in position in the shaft. It will be understood that a soft core 6 is slid on the shaft while the rock member 5 occupies the position shown in Fig. 8, that is, when the parts are not expanded. The core is then held stationary while the shaft is turned to the left in Fig. 8, thereby causing the pins to engage the interior of the core. 10 The shaft is now inserted in the cutting machine and core member 6 is severed into a number of individual cores which are retained in position by the pins. The shaft is then removed from the cutting machine 15 and inserted in a winding machine and the coils of flexible material are wound on the individual cores. During the winding action the direction of rotation is as indicated by the arrow in Fig. 5 and the resistance pull 20 of the unwound web is in the opposite direction; consequently, the parts will retain their position. When the winding action is completed the shaft is removed from the winder and the shaft is turned to the right 25 in Fig. 5 while the coils and cores are held stationary. This will cause the parts to

assume the position shown in Fig. 6 where the coils and cores are released.

I claim:

1. Core-supporting means comprising: a shaft having circumferential grooves in its outer surface, and a core-clamping member mounted in said shaft to move lengthwise and outwardly above the surface of the shaft, said member having cut-away portions 3 that register with the circumferential grooves of the shaft when the member protrudes from the shaft.

2. Core-supporting means comprising: a shaft having circumferential grooves to provide clearance for exterior cutting means, and expandable devices within said shaft to engage, intermediate the grooves, a core member surrounding the shaft and to hold, in undisturbed relation, a group of individual cores produced from said core member.

Signed at New York, in the borough of Brooklyn county of Kings and State of New York, this 8 day of April 1925.

ROBERT McC. JOHNSTONE.
